CLAIM

The ornamental design for a display screen or portion
thereof with graphical user interface, as shown and
described.

DESCRIPTION

The file of this patent contains at least one drawing/photograph
executed in color. Copies of this patent with color
drawing(s)/photograph(s) will be provided by the Office
upon request and payment of the necessary fee.

The FIGURE is a front view of a display screen or portion
thereof with graphical user interface showing the claimed
design.

The outermost broken lines in the FIGURE show a display
screen or portion thereof, and form no part of the claimed
design. The other broken lines in the FIGURE show portions
of the graphical user interface that form no part of the
claimed design.
